UNITED STATES PATENT OFFICE.

CHARLES PERRY, JR., AND NEIL CURRIE, OF SAN ANTONIO, TEXAS.

WATCH BELT-BUCKLE.

1,383,968.

Specification of Letters Patent.

Patented July 5, 1921.

Application filed September 14, 1920. Serial No. 410,100.

To all whom it may concern:

Be it known that we, CHARLES PERRY, Jr., and NEIL CURRIE, citizens of the Republic of Mexico and Canada, respectively, as first above stated, residing at San Antonio, in the county of Bexar and State of Texas, have invented certain new and useful Improvements in Watch Belt-Buckles, of which the following is a specification.

10 This invention relates to a new and useful watch belt buckle.

One of the objects of our invention is directed to a novel belt buckle for retaining a watch therein so that the time may readily be observed and the watch closed.

Another object of our invention relates to a belt buckle of the above type provided with a removable hinged watch which may also be opened or closed with respect to 20 the buckle.

With these objects in view and others which will be manifest and suggested as the nature and purpose of our invention are revealed in the following specification and drawing wherein we have shown a practical, yet preferred embodiment thereof,

Figure 1 is a perspective of the belt buckle and watch, the latter being closed.

Fig. 2 is a view similar to Fig. 1, the 30 watch being open.

Fig. 3 is a view taken on the line 3—3 of Fig. 1.

Fig. 4 is a view taken on the line 4—4 of Fig. 3.

35 Fig. 5 is a view similar to Fig. 4, the watch being open.

Fig. 6 is a modified form of the invention showing the watch inside a buckle.

Similar numerals on the drawing referring to corresponding parts in the specification, numeral 1 designates a belt, having one end secured as at 2 to a curved metal belt buckle 3 and its opposite end 1' passing between its front and rear sides 5, 6 and 45 retained by the strap 7 in the usual and well known manner. The top and bottom flanges 8, 9 of the buckle are provided with diagonal recesses 10 in which the reduced ends 11 of a roller 12 may slide to tighten the 50 belt.

Referring to Figs. 1 and 2, it will be seen that the front side 5 is provided with a circular opening 13 having a beveled edge 13' in which the front face 14 of a watch 15 is 55 retained by a snap catch 16 struck out of the top edge 16', the said catch preferably engaging the stem 17 of the watch. The

watch case is preferably provided with a hook portion 18 integral therewith which is hinged in the recess 19 of the front side 5 intermediate of the belt buckle so that in its normal or closed position the face of the watch will be retained within the opening 13 by the catch. In Figs. 1 and 4 it will also be seen that the stem extends sufficiently above the top flange 8 to permit the winding of the watch without its removal from the buckle. Being hinged to the lower side or front of the buckle, by releasing the stem from the catch, the time may readily be observed and the watch closed as is clearly obvious from Figs. 1 and 2 of the drawing.

In the modified form of our novel buckle watch holder, shown in Fig. 6, we have shown the hooked portion 18^a of the watch 15^a hinged to the vertical pintle 19^a to which the hinge member 2^a is secured. In this form it will be seen that the watch 15^a lies entirely within the buckle and that the belt 1^a passes through the same and in back 80 of the watch. By slightly turning the buckle away from the body of the person, the time may be observed without touching any part of the watch proper.

In the accompanying drawings, we have 85 illustrated our invention embodied in one form by way of example, and which in practice has been found to be highly satisfactory in obtaining the desired results. It will be obvious however, that other embodiments may be adopted, and that various changes in the details of construction may be resorted to by those skilled in the art without departing from the spirit and scope of the invention. It is furthermore understood 90 that the invention is not necessarily limited or restricted to the precise elements shown except in so far as such limitations are specified in the subject matter being claimed.

Having shown and described our invention, what we now claim as new and desire to secure by Letters Patent of the U. S. is:—

In a belt buckle of the class described, having an open, beveled front side, a watch case having an integral hook hinged to the 105 lower edge of said front face, and a catch integral with the front face of said buckle for engagement with the stem of a watch to keep the same in its closed position.

In testimony whereof, we affix our signatures hereto.

CHARLES PERRY, JR.
NEIL CURRIE.
